FOUNTAIN COMB STRUCTURE

William D. Pyle, Indianapolis, Ind.

Application January 22, 1944, Serial No. 519,319

4 Claims. (Cl. 132—13)

This invention relates to a fountain comb.

The chief object of this invention is to provide a valveless comb which is capable of applying, in ordinary use, a liquid to the hair when the latter is drawn through the comb teeth and which comb is of such character that liquid feeding or discharge does not continue when the comb is laid down.

The chief feature of the present invention resides in providing a liquid reservoir positioned laterally of a comb body and extending downwardly toward and partially lapsing the teeth but spaced thereof to form with the teeth a retaining structure for a distributor pad.

Another feature of the invention is that it readily lends itself to incorporation as an attachment to an ordinary comb as well as construction as an integral structure therewith.

Other objects and features of the invention will be set forth more fully hereinafter.

The full nature of the invention will be understood from the accompanying drawing and the following description and claims:

In the drawing

Fig. 1 is a side elevation of an integral embodiment of the fountain comb invention.

Fig. 2 is a transverse sectional view of said embodiment when supported in non-feeding position.

Fig. 3 is a similar view of an attachment and standard or conventional comb embodiment of the invention.

Fig. 4 is a view similar to Fig. 1 of the form illustrated in Fig. 3.

In Figs. 1 and 2 of the drawing 10 indicates a comb body or back portion, 11 the end teeth and 12 the intermediate teeth. Extending laterally from one side of the body portion is the chamber-forming wall means 13 and 14, the former projecting beyond the latter and curving towards same as 15 to form a comb rest portion.

Both portions 15 and 14 are extended towards the teeth as at 17 and 16 respectively and are joined. All of the aforesaid portions of the lateral means together with end wall portions 18 and comb body portion 10 form an elongated chamber or reservoir laterally of said body.

Observe that teeth 12 and portions 14 and 16 form a pad receiving groove which at C has compressive action upon the pad P, of felt, etc. for retention of the pad in the resulting channel or groove. Pad P can be seated by broadside presentation or from either end as desired.

The reservoir herein is illustrated with a plurality of spaced ports 19 which provide restricted

liquid feeding to the absorbent pad. Liquid is supplied to the reservoir through one end opening 20 threaded to receive plug 21. Since reservoir filling should be limited to the lower level of opening 20, see level B, it will be noted that the latter is slightly below the take-off of port 19 so that when the comb is rested upon a support (level A) liquid will not flow to the ports by gravity.

Observe that portions 15 and 17 prevent the pad from contacting the support surface (see level A).

The extension of the reservoir into the groove forming portions 15, 16 and 17 insures that when the comb is inverted, that is with teeth up, liquid will feed to the pad through ports 19 because the liquid, previously in the chamber extension which parallels the teeth, will rise to a level above the reservoir ends of ports 19. Naturally when the comb is held with the teeth down, the liquid will also feed to the pad.

Hence with a "full" reservoir, as determined by level B when the comb is positioned as shown in Fig. 2, the pad will be fed with liquid in all comb positions except that as shown in Fig. 2.

Observe also that the pad laps the teeth, to an appreciable extent, so that hair passing through the teeth are pad engageable for liquid transfer. Also note that since the pad is resilient, and is subject to pressure at C, the opposite face of the pad seats certain portions thereof between the teeth as indicated at 22. For this reason lateral mounting is preferred to end mounting thereof although either can be effected.

Fountain combs with reservoirs in the body portions and carrying pads retained by clamping plates have heretofore been employed but same cannot feed when upside down nor be non-feeding when laid upon one side at rest, all as inherent in the present invention.

Reference will now be had, see Figs. 3 and 4, to an attachment embodiment of the invention. Herein a standard or conventional comb has the back or body portion 110, the end teeth 111 and intermediate teeth 112. Herein the lateral reservoir is formed by an elongated closed chamber structure including walls 114 and 113, the latter curving as at 115 and then turning toward teeth 112 as at 117. Wall 114 also turns toward the teeth 112 as at 116 and the junction C¹ is a clamp formation portion as before for the felt clamping portion.

Top wall 109 and end walls 118 complete the chamber. Access to the reservoir is had by way of opening 120 threaded to receive plug 21, see Fig. 3.

This reservoir feeds to pad P¹ by ports 119 and

the intake end thereof is at a higher elevation (see Fig. 3), than level B¹, the lower level of opening 120 when the comb rests upon the support having level A¹. Note that pad P¹ can be end or laterally presented to and seated and clamping anchored in the resulting groove formed by teeth 111 and 112, walls 114 and 116 and portion C¹. Note that the pad P¹ at 122 expands into the tooth space opposite clamp C¹.

So far except for detachment, the previous modification description applies as well to that illustrated in Figs. 3 and 4. However, herein end walls 118, see Fig. 4, are extended outwardly adjacent comb portion 110 as at 123 and apertured at 124 to pass the screw 125 screwed at 126 into the end of the comb body portion 110. Opposite ends are similarly secured. In view of the elongated character of the chamber, there is provided an external central wall 127, see Fig. 4. Aligned therewith and transverse to cover portion 109 and integral with wall 115 cover 109 is an apertured boss 128, see Fig. 3. A stud with head 130 has its end 131 threaded into the body portion 110 at 132, see Fig. 3.

When the comb is a short one, this central anchor may be the only one necessary. When the comb is longer (intermediate length), the two end anchors may be sufficient. When the comb is ten or twelve inches long, both types may be employed.

The foregoing illustrates and describes how an ordinary or conventional comb may be readily transformed into a fountain comb of the type

illustrated in Figs. 1 and 2 and described hereinbefore together with all of the inherent advantages thereof.

While the invention has been illustrated and described in great detail in the drawing and foregoing description, the same is to be considered as illustrative and not restrictive in character.

The several modifications described herein as well as others which will readily suggest themselves to persons skilled in this art, all are considered to be within the broad scope of the invention, reference being had to the appended claims

The invention claimed is:

1. A fountain comb having substantially co-planar teeth and body portion, means extending laterally of the latter portion and providing a reservoir spaced from such teeth and partially lapping same and in offset and opposed relation thereto to form with the teeth a pad receiving groove, a compressible pad seated in the groove, and passages between the reservoir and groove providing restrictive communication to feed liquid from the reservoir to the pad.

2. A fountain comb as defined by claim 1 wherein said means is integral with the comb body portion.

3. A fountain comb as defined by claim 1 wherein said means is detachably connected to the comb body portion.

4. A fountain comb as defined by claim 1 wherein the reservoir is L-shaped in cross-section.

WILLIAM D. PYLE.
